UNITED STATES PATENT OFFICE.

CHARLES D. McARTHUR, OF PITTSBURGH, PENNSYLVANIA, ASSIGNOR TO BLAW COLLAPSIBLE STEEL CENTERING COMPANY, OF PITTSBURGH, PENNSYLVANIA, A CORPORATION OF NEW JERSEY.

PAVING-FORM.

1,142,043.

Specification of Letters Patent. Patented June 8, 1915.

Application filed September 11, 1911. Serial No. 646,787.

To all whom it may concern:

Be it known that I, CHARLES D. McARTHUR, a citizen of the United States, residing at Pittsburgh, in the county of Allegheny and State of Pennsylvania, have invented certain new and useful Improvements in Paving-Forms, of which the following is a specification.

The invention relates to paving forms and particularly to those adapted for use in the formation of curbs, gutters and sidewalks. The invention has for its objects; the provision of an improved form of mold of simplified construction which may be constructed at a minimum cost and may be assembled and disassembled with convenience and rapidity. One embodiment of the invention is illustrated in the accompanying drawings, wherein:—

20 Figure 1 is a perspective view showing both the sidewalk and curb and gutter forms; Fig. 2 is a side elevation of one of the side sections employed in the mold; Fig. 3 is a plan view of a portion of the side section; Fig. 4 is an end view of the side section; and Figs. 5 and 6 are side elevations of the spacing plates employed with the sidewalk and curb and gutter forms respectively.

30 Referring first to the sidewalk form, 1 and 2 are the side sections, preferably channel bars; and 3—3 are what may be termed spacing plates, such spacing plates being placed at suitable intervals along the length 35 of the side sections, and secured to such side sections in the manner to be hereinafter described.

As indicated in Fig. 5, each spacing plate 2 is provided at each end with a lug or ear 4 having a perforation 5 therethrough. The end edges of the side plates 3 abut against the inner faces of the side sections 1 and 2, while the upper portions of the webs of the sections and their flanges are slotted at 3' to receive the ears or lugs 4, so that the spacing plates may be positioned or removed by a vertical movement. Wedges 6 (Fig. 1) extend through the perforations 5 in the lugs 4 after the spacing plates have been positioned, such wedges 6 lying beneath the flanges of the channel bars 1 and 2, so that the spacing plates are not only securely locked against endwise movement, but are also held against vertical movement. Where

the side members 1 and 2 are made up 55 of more than one section placed end to end, such sections are secured together in the manner indicated in Figs. 2 and 4, the opposing sections being provided with straps 7 whose ends are turned at right angles to 60 the side members as indicated at 8, and are slotted to receive bolts 9.

In order to brace the spacing plates 2 and 3 against tilting movement, the rivets 10 and 11 are provided (Figs. 1, 2 and 3), 65 with their heads spaced apart sufficiently to receive the edge of the spacing plate. A simple and inexpensive means is thus provided for securely maintaining the spacing plates against lateral or tilting movement. 70 The close spacing of the slots 3' permits of the adjustment of the plates 3.

The curb and gutter form indicated in Figs. 1 and 6 is quite similar in construction to the sidewalk form just described. The inner side section however, is made up of two channel bars 12 and 13 bolted together in the position indicated in Fig. 1. The outer side member 14 corresponds in all respects to the side sections or members 1 and 2 here- 80 tofore described in connection with the sidewalk form. The wood member 15' serves to form the outer face of the curb, such member 15 being held in position with respect to the side sections 12 and 14 by means of suitable 85 supporting braces or brackets (not shown). Transverse spacing plates 15 are provided at intervals, such plates being provided with lugs or ears 16 corresponding to the lugs or ears 41 in the sidewalk form. It will be 90 seen that in both constructions the spacing plates serve to maintain the side members or sections rigidly in their proper positions, and that after the concrete has set the spacing plates may be readily removed, while the 95 side sections are left in position, or vice versa.

Having thus described my invention and illustrated its use, what I claim as new and desire to secure by Letters Patent is the following:—

1. In combination in a paving form, a longitudinally extending member and an opposing longitudinally extending member comprising two channel irons with their 105 ends spaced apart and their flanges turned outwardly, means for detachably securing the two adjacent ends of the channels to-

gether, a vertically movable spacing plate between the two members and having a perforated lug portion fitting between the said adjacent ends of the channel, and a removable holding member extending through the perforation in the lug portion and lying beneath the upper flanges of the channels.

2. In combination in a paving form, a pair of substantially parallel metal sections having vertical web portions and horizontal outwardly projecting flanges at their upper edges, one of such sections having a slot extending through the flange and web, a vertically removable spacing plate extending between the sections and having one end fit-

ting against the slotted section and provided with a perforated lug fitting the slot when the plate is in position, and a holding member extending through the perforation in the lug and lying beneath the flange so as to bear against the flange and web and maintain the plate against vertical and endwise movement.

In testimony whereof I have hereunto signed my name in the presence of the two 25
subscribed witnesses.

CHARLES D. McARTHUR.
